MANIFOLDING REGISTER

William G. Borchers, Hoboken, N. J., assignor to
Autographic Register Company, Hoboken,
N. J., a corporation of New Jersey

Application September 5, 1940, Serial No. 355,417

20 Claims. (Cl. 282—21)

This invention relates to manifolding.

An object of the invention is to provide improved means for feeding a plurality of continuous strips over a writing platen, automatically stopping the advance of the strips when each has been fed a form length and also for adjusting the strips in accurate registration with each other and with severing means for tearing the strips along a predetermined severing line.

Heretofore this was accomplished by providing in the body of each form length of the record strips one or more apertures through which annular feeding means extends, said means becoming inoperative thereby to advance said strip or strips until the said strips are restarted by auxiliary means. The purpose of the auxiliary means is to move the record strips sufficiently in feeding direction to shift the said apertures beyond the feeding means. Thus when each feeding operation is complete, the form lengths of the strip are halted and maintained in registration by entrance of the feeding means into the apertures of the superposed strips in one set of form lengths. The strips are advanced against the tension of retarding means which are intended to prevent overthrow of the strips and attendant malregistration.

However, in manifolding registers of this type, difficulty has been encountered especially in feeding manifolding stationery in which the superposed strips possessed different physical characteristics, for instance, different weight or different surface properties. It has been found under these conditions that it is difficult to adjust the register so that all of the forms are properly aligned and so that overthrow beyond a predetermined tear-off point does not occur.

These difficulties are aggravated by variations in the manner of operating manifolding registers by different operators. Some operators turn the feeding means slowly and smoothly, while others use a rapid and more or less jerky motion. As will hereinafter appear, this difficulty has been overcome by provision of novel and improved feeding means according to the present invention.

An object of the present invention is to provide feeding means which operates in a novel and valuable way during the feeding of each form length of a plurality of strips and particularly during the concluding part of each form-feeding operation.

More specifically, an object of the present invention is to provide, in combination with a main feeding means becoming inoperative to further advance the superposed strips upon entering

form-registering apertures in each form length of said strips for partially registering said strips with each other, an auxiliary feeding means for resuming advancement of the said strips after said main feeding means has become inoperative as just stated, said auxiliary feeding means becoming itself inoperative by reason of its entering secondary feed-arresting form-registering apertures in longitudinal alignment with the first-named apertures in the same form length whereby the superposed strips are accurately registered both in transverse and longitudinal direction before a severing line between successive form lengths reaches a predetermined severing station on the machine; said main feeding means reengaging the strips as said severing line attains said severing station to again resume the strip advancement for feeding the next form length.

Another object of the present invention is to provide in combination with the improved means of the kind described for advancing a plurality of record strips one form length for each operation thereof, means for stopping such advancing means after each successive form length of a plurality of superposed record strips has been advanced to a predetermined position.

Still another object of the invention is to provide strip-advancing means capable of operating as hereinbefore described, including a strip feeding means, for instance, feed disks, the operative peripheries of which engage the strip closely adjacent to the margins thereof, whereby the use of marginal notches or indentations on the strips as feed-arresting apertures is made possible.

In attaining the foregoing and other objects, the present invention provides an exceedingly sturdy, dependable and inexpensive feeding means. The said main and auxiliary feeding means are adapted by cooperating with two longitudinally aligned sets of feed-arresting, form-registering apertures in each form length to interrupt advancement of the said strips twice during each form length feeding operation, upon entering said sets of alterations, engagement of the main feeding means with the first set registering said strips in longitudinal direction and of the auxiliary feeding means with the second set of alterations registering the strips accurately both in transverse and longitudinal direction, each time a set of forms is advanced to a position for removal, by a continuous movement in a single direction of a single actuator, preferably by a single rotation of a handle offset from a rotary shaft.

In my copending application, Serial No. 339,418, filed June 8, 1940, which has matured into United States Patent No. 2,231,106 issued Feb. 11, 1941, which discloses one embodiment of this invention, the mechanism is so provided that the sets of physical alterations in the manifolding stationery are spaced apart from each other transversely across said strips and main feeding means are aligned with one set of alterations while auxiliary feeding means are aligned with the other set of alterations.

In the embodiment of this invention, herein disclosed, the arrangement is such that two sets of alterations in each form length may be longitudinally aligned with each other. This permits the incorporation of both main and auxiliary feeding means in a single operator, such as a feed disk, said disk being operably associated with means for reengaging each of said feeding means with the strips of stationery to resume strip advancement after each form-registering interruption thereof.

The physical alterations in the strips of stationery are preferably located near the longitudinal edges of the strips and when this is done the provision of the two sets of alterations in longitudinal alignment provides additional space for printed matter in the area in which the printing usually occurs in-between the longitudinal margins of the strips.

Further advantages and objects will be appreciated from the following description referring to the illustrative embodiments shown in the accompanying drawings, in which:

Figure 1 is a plan view, partially in cross-section, of a form of manifolding device according to the invention, showing in dotted lines the location of feeding disks carrying restarting shoes which constitute main and auxiliary feeding means adapted to engage manifolding strips marginally notched and apertured at both sides of the strip, portions of the strips being cut away to show underlying portions of the machine.

Fig. 2 is a longitudinal vertical section substantially along the line 2—2' of the device of Fig. 1.

Fig. 3 is a fragmentary detail of a manifolding strip showing in dotted lines the initial position of the main feeding means for feeding a form length of manifolding stationery.

Fig. 4 is a similar to Fig. 3, but shows the position of the main feeding means as the strip advancement is interrupted for the first time in the feeding of a form length.

Fig. 5 is also similar to Fig. 3, but shows the position of the feeding mechanism as the auxiliary feeding means engages the record strip.

Fig. 6 is likewise similar to Fig. 3, but shows the position of the feeding mechanism after strip advancement is halted for the second time during the feeding of a form length by the auxiliary feeding means entering a secondary set of alterations for accurate registration of the superposed strips and the main feeding means is about to engage the manifolding strips.

Fig. 7 is a perspective view of the feeding means in the position shown in Fig. 3.

Fig. 8 is a perspective view similar to Fig. 7, showing the position of the feeding means as indicated in Fig. 4.

Fig. 9 is a perspective view of the feeding means in a position corresponding to that shown in Fig. 5.

Fig. 10 is a perspective view of the feeding

means in the position corresponding to Fig. 6.

Fig. 11 is an enlarged fragmentary view in cross-section substantially along the line 2—2' in Fig. 1, showing in detail a tensioning and retarding means for the superposed strips of manifolding stationery.

Referring to Figs. 1, 2, and 11 which exemplify an embodiment of the manifolding device according to the present invention, the same is shown as including a casing 10, having a storage compartment 11, containing a stack 12 of zigzag folded multiple manifolding strips 13 crossed at form-length intervals by severing lines 14, which may be suitably formed by perforations in the superposed strips.

These form lengths are arranged in the device according to practice well understood in the art. The superposed strips 13 are carried above a platen 16 and interleaved with transfer sheets 13a which may be supported in any manner known in the art. After successive form lengths, e. g. 15a and 15b, have been given the desired notations while positioned on the platen 16, the strips are advanced to bring a following set of forms into a like position on the platen. The lowermost of the superposed strips is diverted downward by means of a deflector 17 into a record storage compartment 18 while the other strips are advanced over the top of said deflector to rest upon the forward roof 19 of the casing and adjusted to bring the severing line 14 between successive form lengths under a severing edge 20 carried by a margin or cover plate 22 which extends over the feeding mechanism. The diverted lowermost strip is refolded in a stack 21 in a record storage compartment.

Details of the casing are unimportant, and the showing thereof is more diagrammatical than otherwise to simplify the drawings. However, it may be further pointed out that the manifolding strips 13 in approaching the platen 16 pass over a guide roller 23 and a plurality of guide rollers 24 and 24a beneath the cover and margin plate 22.

Each of the guide rollers 24 carries at its mid-portion a thin tensioning plate 43 pivotally attached to the roller by a hooked flange and adapted to extend from the top of the roller between the superposed strips of manifolding material 13 a short distance over the receiving end of the platen 16. A resilient finger 44 affixed to the undersurface of the cover plate 22 in alignment with said tensioning plates exerts pressure on the topmost strip compressing the superposed strips and interleaved tensioning plates against the end of the platen. The several strips are thus subjected to an equal retarding tension to prevent overthrow of the strips and consequent malregistration thereof.

The feeding means comprises a pair of disks 25 which engage the underside of the lowermost sheet of the multiple record strip 13 cooperating with overlying rollers 26 fixed on a rotating shaft 27, the ends of which are suitably mounted for rotation in vertical slotted extensions 28 of vertical bearing plates 29. The roller shaft 27 is urged downward by springs, not shown, but familiar in the art to effect engagement of the uppermost record strip by said rollers.

The action of the said springs compresses the record strips between said disks and feed rollers whereby the feed disks are adapted to advance the strips upon rotation at a rate equal to the peripheral speed of said disks.

The feed disks 25 are adapted to rotate at the

same peripheral speed as the rollers 26, suitable gearing being provided therefor. The disks 25 are secured on a rotary shaft 30 journaled at each end through the bearing plates 29. A gear 31 is fixed on said shaft and said gear meshes with a suitable pinion 32 secured to the shaft 27. The operating shaft 30 has a crank arm 33 fixed thereon carrying a handle 34 to facilitate manual rotation of said shaft.

It will be noted that record strips 13 are shown as having marginal cutaway portions or notches 35 coincident with the severing lines 14 between successive form lengths thereof as indicated in Fig. 1. Directly behind said cutaway portions and in longitudinal alignment therewith, a pair of circular apertures 39 are provided near the edge of each form length. In Fig. 1, the said disks 25 which are indicated by dotted lines and the corresponding rollers 26 are spaced transversely of the machine so that they register with the marginal cutaway portions or notches 35 and with the circular apertures 39 of the record strips 13.

In order to guide the strips 13 over the ends of the interleaved transfer sheets 13a and to prevent catching of the marginal notches 35 or apertures 39 thereon, each of the guide rollers 24 carries at each end a pair of flaps 45 of smooth surfaced fabric which extend forward a short distance above and below each of the transfer sheets 13a. Thus the said flaps guide the margins of each strip over the transfer sheets preventing the notches 35 and apertures 39 of the manifolding strips from contacting the forward ends of said transfer sheets and insuring smooth feeding of the strips to a position above the platen.

Each of the feed disks 25 is provided with a pair of laterally extending starting shoes 36 and 37, the outer surfaces of which constitute lateral extensions of the peripheral feeding surface of the said disks. The said shoes extend inward with reference to the margin of the manifolding strips beyond the notches 35 and apertures 39 and rollers 26 are correspondingly extended in such a manner that the said shoes cooperate with said rollers to engage the manifolding strips when either of the shoes has reached a position below said rollers.

The shoes 36 as well as the shoes 37 on the respective feeding disks 25 are in transverse alignment with each other, but the said shoes are spaced apart angularly upon each of said disks by a distance slightly exceeding the spacing between the notches 35 and apertures 39. The shoe 36 and the minor feeding periphery of the disk 25 between the shoe 36 and the shoe 37 constitute the auxiliary feeding means, while the shoe 37 and the major feeding periphery of the disk 25 between the shoe 37 and the shoe 36 constitute the main feeding means. Thus, after strip advancement by the main feeding means is interrupted by entrance of the major feeding surface of feed disks 25 and rollers 26, into notches 35, shoe 36 cooperates with roller 26 upon continued rotation of the feed disks to re-engage the said manifolding strips with the minor feeding surface of the disks, moving the said notches beyond the bite of said rollers and disks and resuming advance of the stationery by the auxiliary feeding means. As the minor feeding surface of feed disks 25 and rollers 26 enter the apertures 39, strip advancement is again interrupted until shoes 37 and rollers 26 engage the said strips upon continued rotation

of the disks 25, whereby the said apertures are moved beyond the bite of said rollers and disks and the strip advancement by the main feeding means is again resumed.

Upon entrance of the feed disks 25 and rollers 26 into the notches 35, said disks and rollers cooperate with the transverse leading edge of the said notches, tending to register the superposed strips in longitudinal direction. Registration, however, as hereinbefore stated, is often not effective to accurately register the superposed strips. Entrance of the said disks and rollers into the circular apertures 39, however, reregisters the said strips both in longitudinal and transverse direction and accurately positions the said strips. Such registration and reregistration preferably occurs before the severing line 14 between the successive form lengths has reached the tearing edge 20, and preferably restarting shoes 37 or disks 25 reengage the said strips before the severing line 14 reaches said tearing edge.

Releasable stop means are provided to halt rotation of the shaft 30 as the severing line 14 reaches a position below the tearing edge 20 as set forth in the foregoing description. This occurs just after the feed disks 25 or shoes 37 have reengaged the record strips 13, after strip advancement has been interrupted by apertures 39. The stop means may be of any suitable construction, several forms of which are well known in the art. For instance, as indicated by dotted lines in Fig. 2, stop means may be of the form shown in my copending application Serial No. 112,511, filed November 24, 1936, which has matured into United States Patent No. 2,212,853, issued August 27, 1940, according to which two pins 41 and 42 are mounted in a housing 43 fastened to the interior wall of a casing 10, said pins being interconnected so as to be alternately projected into the path of the crank 33 carried by the operating shaft 30 of the feed mechanism. A spring, not shown, normally urges pin 41 into projected position while pin 42 is retained in retracted position. Pin 41 is bevelled on the forward side which initially engages the crank 33 as it is rotated in forward direction so that the handle upon engaging said bevelled surface pushes pin 41 into retracted position while pin 42 is projected in such a manner as to engage said crank. The latter pin 42 acts as a stop, halting further motion of the crank. However, since the said pins are spaced apart a distance slightly greater than the width of the handle 33, the pin 41 is released by the handle as soon as it strikes pin 42. Thus, as the handle is released by the operator in the final stopping position, the aforesaid spring retracts pin 42, again projecting pin 41, and leaving the handle free to feed the next form length of manifolding stationery.

Figs. 3 to 6 and corresponding Figs. 7 to 10 inclusive show a feed roller and feed disk, the latter carrying a pair of restarting shoes, in the consecutive positions which they occupy during the feeding operation.

Consecutive operation of the machine described and illustrated herein is as follows:

Referring to Figs. 3 and 7, a manifolding strip 13 is shown in its initial position, the stop means, for instance, pins 41 and 42 referred to in the foregoing description, having arrested the crank 33 in the final position and form length 15' of the manifolding stationery being disposed for issuance. The minor feeding periphery of feed

disk 25 and roller 26, constituting the auxiliary feeding means, have entered aperture 39 in the following form length 15 of the manifolding strip to effect accurate registration of the various superposed strips in transverse as well as longitudinal direction and shoe 37, which constitutes a part of the main manifolding means, has reengaged said strip for moving the aperture 39 beyond the bite of the feed roller 26 and feed disk 25. The resulting forward motion has advanced the strips slightly to bring the severing line 14 under the tearing edge of the manifolding machine.

The issued form length 15' of the manifolding strip 13 may be torn off along the severing line 14, engagement of the shoe 37, and rollers 26, at opposite sides of the strip preventing displacement of the said strip, and the friction of the movable parts of the feed mechanism preventing rotation thereof by the tension applied to the strips 13 during such tearing operation.

After inscription of the succeeding form length 15, the operating shaft 30 and crank 33 are rotated by turning the handle 34, the major feeding periphery of feed disks 25 cooperating with rollers 26 to advance the form length 15. Said form length is shorter than the major operative periphery of the disk 25 between the shoe 37 and the shoe 36. Hence, before completion of one revolution of the shaft and before shoe 36 reaches a position below roller 26, notch 35 has moved to the position shown in Figs. 4 and 8 between the feed disk and roller 26 rendering the main feeding means inoperative to advance the strip further. Entrance of the feed disk and roller into said notch effects a degree of registration of the superposed strips, especially in lengthwise direction. However, such registration is often not accurate especially when the strips are of different physical characteristics or if the operation of the feed is relatively rapid, jerky or variable.

Rotation of the operating shaft 30 is continued, the strips 13 remaining stationary until shoe 36 moves into a position to engage strips 13 between its operative surface 36a and the roller 26 as shown in Figs. 5 and 9. By this means, advancement of the strip by the auxiliary feeding means is resumed, notch 35 being moved beyond the bite of the roller 26 and feed disk 25, and the strips advanced a short distance until said roller and disk enter feed-arresting, form-registering aperture 39 in the strips as shown in Figs. 6 and 10. As roller 26 and the minor feeding periphery of disk 25 enter aperture 39, complete and accurate registration of the superposed sheets with each other in transverse and longitudinal directions is effected. The severing line 14 between form lengths 15 and 15'' is moved by the aforesaid operation to a position just in advance of the tearing edge 20.

As rotation of the handle 34 completes one revolution, shoe 37 and roller 26 reengage the said strips moving the strip forward by a slight increment into a position shown in Figs. 3 and 7. The severing line 14 is thereby accurately positioned below the tearing edge 20. The stop means hereinbefore described operates to arrest rotation of the handle 34 and crank 33 when this position is attained. The mechanism is now in a position for tearing off the issued form lengths, the main feeding means having reengaged the succeeding form length 15'' by moving aperture 39 beyond the bite of roller 26 and feed disk 25.

If desired, by suitable disposition of the stop

means, the final increment through which the strip is moved to bring the severing line 14 below the tearing edge 20 may be decreased until it is substantially nil, the final position of said severing line being attained when shoe 37 and roller 26 have just reengaged the strips 13 after said strips have been reregistered by entrance of feed disks 25 and roller 26 into apertures 39. Similarly said increment may be somewhat increased, shoe 37 moving just beyond roller 26, and feed disk 25 engaging the strips in cooperation with roller 26.

Other forms of stop means, for instance, a detent or manually releasable stop means may be substituted for the automatic releasing stop means hereinbefore described.

Instead of providing notches for the purpose of initially arresting operation of the feeding means, apertures of any form may be used. Marginal notches, however, are preferred, since they require fewer dies for manufacturing the multiple record strips than apertures provided in the body of said strips. The said notches preferably coincide with the severing lines 14 to facilitate tearing of the issued record strips 13 along the tearing edge 20 and also to facilitate the zig-zag folding of the manifolding stationery.

It is not necessary that one edge of notches 35 be made perpendicular to the margins of the record strips, as shown. This form of notch effects better registration in the form of longitudinal direction, but since accurate registration is effected according to the present invention by the secondary circular apertures, the said edges may be cut at an angle other than a right angle to the edges of the stationery.

Furthermore, it is possible to dispose the sets of feed-arresting alterations transversely of the strip, in any portion thereof. However, marginal alterations are preferred in order to effect better registration of the superposed sheets, and to permit more space in each form length for printing. While in the machine illustrated in my copending application Serial No. 339,418, above referred to, the two sets of feed-arresting, form-registering alterations are spaced from each other transversely of the sheet, it is often desirable to avoid such spacing of two sets of alterations of apertures in order to provide room for printing on each form length of the manifolding stationery. In the embodiment of my invention, illustrated and described herein, it is possible to provide two sets of physical alterations in the manifolding strip which are longitudinally aligned with each other and which, as hereinbefore stated, may be positioned adjacent the margin of the sheets, leaving the central portion of the strips free for desired indicia.

Since starting and stopping of the writing strips depend solely upon the position of the apertures and notches therein, forms of any sheet length may be used provided such sheet lengths are less than the major operative periphery of the feed disks 25 between the shoes 37 and 36, in order that one revolution of the feeding means should advance the strip by one form or sheet length. However, if longer form lengths are used, exceeding the total periphery of the disks 25, the machine may be operated to effect similar registration of the superposed form lengths, but more than one revolution of the feed mechanism is required to feed one form length of such stationery.

Variations and modifications may be made within the scope of this invention and portions of the improvements may be used without others.

I claim:

1. In a manifolding machine, a platen adapted to support a plurality of superposed continuous strips each divided into a series of form lengths by transverse severing lines, each form length having a plurality of feed-arresting, form-registering physical alterations in mutual longitudinal alignment; and means for advancing said plurality of strips, said means being aligned with said physical alterations, and including a main feeding means cooperating with certain of said physical alterations to interrupt feeding of said strips and to bring the superposed form lengths of the several strips into registration before a severing line between two form lengths reaches a predetermined position on the machine, and supplementary feeding means for resuming advancement of said strips, the latter means cooperating with the other physical alterations to again interrupt the feeding of said strips and to accurately reregister the superposed form lengths by the time said severing line reaches said predetermined position.

2. In a manifolding machine, a platen adapted to support a plurality of superposed continuous strips each divided into a series of form lengths by transverse severing lines, each form length having a plurality of feed-arresting, form-registering physical alterations in mutual longitudinal alignment; and means for advancing said plurality of strips, said means being aligned with said physical alterations and including a main feeding means cooperating with certain of said physical alterations to interrupt feeding of said strips and to bring the superposed form lengths of the several strips into registration before a severing line between two form lengths reaches a predetermined position on the machine, and supplementary feeding means for resuming advancement of said strips, the latter means cooperating with the other physical alterations to again interrupt the feeding of said strips and to accurately reregister the superposed form lengths by the time said severing line reaches said predetermined position; said main feeding means again resuming advancement of said strips after the latter interruption in the feed thereof.

3. In a manifolding machine, a platen adapted to support a plurality of superposed continuous strips each divided into a series of form lengths by transverse severing lines, each form length having a plurality of feed-arresting, form-registering physical alterations in mutual longitudinal alignment; and means for advancing said plurality of strips, said means being aligned with said physical alterations and including a main feeding means cooperating with certain of said physical alterations to interrupt feeding of said strips and to bring the superposed form lengths of the several strips into registration before a severing line between two form lengths reaches a predetermined position on the machine, and supplementary feeding means for resuming advancement of said strips, the latter means cooperating with the other physical alterations to again interrupt the feeding of said strips and to accurately reregister the superposed form lengths by the time said severing line reaches said predetermined position, said auxiliary feeding means moving the first-named alterations beyond the bite of the main feeding means and the main feeding means moving the latter set of alterations beyond the bite of the auxiliary feeding means to permit resumption of the feed

by said main and auxiliary feeding means respectively.

4. In a manifolding machine, a platen adapted to support a plurality of superposed continuous strips each divided into a series of form lengths by transverse severing lines, each form length having a plurality of feed-arresting, form-registering physical alterations in mutual longitudinal alignment; and means for advancing said plurality of strips, said means being aligned with said physical alterations and including a main feeding means cooperating with certain of said physical alterations to interrupt feeding of said strips and to bring the superposed form lengths of the several strips into registration before a severing line between two form lengths reaches a predetermined position on the machine, and supplementary feeding means for resuming advancement of said strips, the latter means cooperating with the other physical alterations to again interrupt the feeding of said strips and to accurately reregister the superposed form lengths by the time said severing line reaches said predetermined position, said main feeding means again resuming advancement of said strips after the latter interruption in the feed thereof, and said main and auxiliary feeding means engaging said strips alternately for advancement thereof.

5. In a manifolding machine, a platen adapted to support a plurality of superposed continuous strips each divided into a series of form lengths by transverse severing lines, each form length having a plurality of feed-arresting, form-registering physical alterations in mutual longitudinal alignment; and rotary means for advancing said plurality of strips, said means being aligned with said physical alterations and including a main rotary feeding means cooperating with certain of said physical alterations to interrupt feed of said strips and to bring the superposed form lengths of the several strips into registration before a severing line between two form lengths reaches a predetermined severance point on the machine, and supplementary rotary feeding means for resuming advancement of said strips, the latter means cooperating with the other physical alterations to again interrupt the feeding of said strips and to accurately reregister the superposed form lengths by the time said severing line reaches said predetermined position, one rotation of said feeding means effecting advancement of said strips by one form length.

6. In a manifolding machine, a platen adapted to support a plurality of superposed continuous strips each divided into a series of form lengths by transverse severing lines, each form length having a plurality of feed-arresting, form-registering physical alterations in mutual longitudinal alignment; a severance station on the machine; means for advancing said plurality of strips, said means being aligned with said physical alterations, and including a main feeding means cooperating with certain of said physical alterations to interrupt the feed of said strips and to bring the superposed form lengths of the several strips into registration before a severing line between two form lengths reaches said severance station on the machine, and supplementary feeding means for resuming advancement of said strips, the latter means cooperating with the other physical alterations to again interrupt the feeding of said strips and to accurately reregister the superposed form lengths by the time said severing line reaches said severance

station; common driving means for said main and supplementary feeding means; and means for releasably stopping operation of said driving means when said severing line has reached said severance station on the machine.

7. In a manifolding machine, a platen adapted to support a plurality of superposed continuous strips each divided into a series of form lengths by transverse severing lines, each form length having a plurality of feed-arresting, form-registering physical alterations in mutual longitudinal alignment; a severance station on the machine; means for advancing said plurality of strips, said means being aligned with said physical alterations, and including a main feeding means cooperating with certain of said physical alterations to interrupt the feed of said strips and to bring the superposed form lengths of the several strips into registration before a severing line between two form lengths reaches said severance station on the machine, and supplementary feeding means for resuming advancement of said strips, the latter means cooperating with the other physical alterations to again interrupt the feeding of said strips and to accurately re-register the superposed form lengths by the time said severing line reaches said severance station, said main feeding means again resuming advancement of said strips after the latter interruption of the feed; common driving means for said main and supplementary feeding means; and means for releasably stopping operation of said driving means when said main feeding means has reengaged the strip and said severing line has reached said severance station on the machine.

8. In a manifolding machine, a platen adapted to support a plurality of superposed continuous strips each divided into a series of form lengths by transverse severing lines, each form length having two sets of feed-arresting, form-registering alterations longitudinally aligned and spaced apart in each form length, and each set being transversely aligned across said strips; means for advancing said strips, said means being aligned with said physical alterations and including a main feeding means cooperating with one set of said physical alterations to interrupt feeding of said strips and to bring the superposed form lengths of the several strips into longitudinal registration before a severing line between two form lengths reaches a predetermined position on the machine, and supplementary feeding means for resuming advancement of said strips, the latter means cooperating with the other set of physical alterations to again interrupt feeding of said strips and to accurately re-register the superposed form lengths both in longitudinal and transverse direction by the time said severing line reaches said predetermined position.

9. In a manifolding machine, a platen adapted to support a plurality of superposed continuous strips each divided into a series of form lengths by transverse severing lines, each form length having two sets of feed-arresting, form-registering alterations longitudinally aligned adjacent the margins of said strip and spaced apart in each form length, and each set being transversely aligned across said strips; means for advancing said strips, said means being aligned with said physical alterations and including a main feeding means cooperating with one set of said physical alterations to interrupt feeding of said strips and to bring the superposed form

lengths of the several strips into longitudinal registration before a severing line between two form lengths reaches a predetermined position on the machine, and supplementary feeding means for resuming advancement of said strips,

5 the latter means cooperating with the other set of physical alterations to again interrupt feeding of said strips and to accurately reregister the superposed form lengths both in longitudinal and transverse direction by the time said severing line reaches said predetermined position.

10. In a manifolding machine, a platen adapted to support a plurality of superposed continuous strips each divided into a series of form lengths by transverse severing lines and each form length having two sets of feed-arresting, form-registering alterations, said sets of physical alterations being spaced apart and mutually aligned longitudinally of said strips; means for advancing said plurality of strips, said means being aligned with both of said sets of alterations and cooperating successively therewith to interrupt the advancement of said strips during the feeding of each form length for accurately registering said superposed strips transversely and longitudinally by the time a transverse severing line between two successive form lengths attains a predetermined position on the machine; and restarting means for moving each of said sets of alterations beyond the bite of said strip-advancing means for resuming advancement of said strips.

11. In a manifolding machine, a platen adapted to support a plurality of superposed continuous strips each divided into a series of form lengths by transverse severing lines and each form length having two sets of feed-arresting, form-registering alterations, said sets of alterations being spaced apart lengthwise and mutually aligned longitudinally of said strips; rotary means for advancing said plurality of strips, said means being aligned with both of said sets of alterations and cooperating successively therewith to interrupt the advancement of said strips twice during feeding of each form length for accurately registering said superposed strips transversely and longitudinally by the time a transverse severing line between two successive form lengths attains a predetermined position on the machine; and a pair of restarting means carried by said rotary means and spaced apart by a distance greater than the longitudinal spacing of said sets of alterations in each form length of said strips, the latter means moving each of said sets of alterations beyond the bite of said strip-advancing means for resuming advancement of said strips.

12. In a manifolding machine, a platen adapted to support a plurality of superposed continuous strips each divided into a series of form lengths by transverse severing lines and each form length having two sets of feed-arresting, form-registering alterations, said sets of physical alterations being spaced apart and mutually aligned longitudinally of said strips; a severance station on said machine; means in advance of said severance station for advancing said plurality of strips toward said severance station, said means being aligned with both of said sets of alterations and cooperating successively therewith to interrupt the advancement of said strips twice during the feeding of each form length for accurately registering said superposed strips transversely and longitudinally by the time a transverse severing line between two successive

form lengths attains said severance station on the machine; restarting means for moving each of said sets of alterations beyond the bite of said strip-advancing means for resuming advancement of said strips; common driving means for said strip-advancing means and for said restarting means; and releasable stop means for automatically halting operation of said driving means when the said severing line reaches said severance station on the machine.

13. In a manifolding machine, a platen adapted to support a plurality of superposed continuous strips each divided into a series of form lengths by transverse severing lines and each form length having two sets of feed-arresting, form-registering alterations, said sets of alterations being spaced apart and mutually aligned longitudinally of said strips; a severance station on said machine; means for advancing said plurality of strips toward said severance station, said means being aligned with both of said sets of alterations and cooperating successively therewith to interrupt the advancement of said strips twice during the feeding of each form length for accurately registering said superposed strips transversely and longitudinally by the time a transverse severing line between two successive form lengths attains said severance station on the machine; and restarting means for moving each of said sets of alterations beyond the bite of said strip-advancing means for resuming advancement of said strips, said restarting means reengaging said strips by the time said severing line reaches said severance station.

14. In a manifolding machine a platen adapted to support a plurality of superposed continuous strips each divided into a series of form lengths by transverse severing lines and each form length having two sets of feed-arresting, form-registering alterations, said sets of alterations being spaced apart and mutually aligned longitudinally of said strips; means for advancing said plurality of strips comprising a plurality of feed disks carried by a rotary shaft, said disks being in alignment with said feed-arresting, form-registering alterations, and a roller cooperating with said disks, said strip-advancing means cooperating successively with said sets of alterations to interrupt the advancement of said strips twice during the feeding of each form length for accurately registering said superposed strips transversely and longitudinally by the time a severing line between the two successive form lengths attains a predetermined severance point on the machine; and restarting means comprising a pair of starter shoes carried by said shaft and arcuately spaced apart by a distance greater than the spacing of said sets of alterations, and a roller cooperating with said shoes for moving each of said sets of alterations beyond the bite of said feed disks and feed roller for resuming advancement of said strips.

15. In a manifolding machine, a platen adapted to support a plurality of superposed continuous strips each divided into a series of form lengths by transverse severing lines and each form length having two sets of feed-arresting, form-registering alterations, said sets of alterations being spaced apart and mutually aligned longitudinally of said strips; a severing station upon said machine; means for advancing said plurality of strips toward said severing station comprising a plurality of feed disks carried by a rotary shaft, said disks being in alignment with said feed-arresting, form-registering alterations,

5 and a roller cooperating with said disks, said feed disks and roller cooperating successively with said sets of alterations to interrupt the advancement of said strips twice during the feeding of each form length for accurately registering said superposed strips transversely and longitudinally by the time a severing line between two successive form lengths attains said severing station on the machine; restarting means comprising a pair of starter shoes carried by said shaft and arcuately spaced apart by a distance greater than the spacing of said sets of alterations, and a roller cooperating with said shoes for moving each of said sets of alterations beyond the bite of said feed disks and feed roller for resuming advancement of said strips; and releasable stop means for arresting the operation of said strip-advancing and restarting means when said severing line reaches said severing station on the machine, said strips being reengaged by said strip-advancing means by the time said severing line attains said severing station.

16. In a manifolding machine, a platen adapted to support a plurality of superposed continuous strips each divided into a series of form lengths by transverse severing lines and each form length having two sets of feed-arresting, form-registering alterations, said sets of alterations being spaced apart and mutually aligned longitudinally of said strip; means for advancing said plurality of strips comprising a plurality of feed disks carried by a rotary shaft, said disks being in alignment with said feed-arresting, form-registering alterations and a roller cooperating with said disks, said feed disks cooperating successively with said sets of alterations to interrupt advancement of said strips twice during the feed of each form length for accurately registering said superposed strips transversely and longitudinally by the time a severing line between two successive form lengths attains a predetermined severance point on the machine; and restarting means comprising a pair of starter shoes carried by said feed disks and arcuately spaced apart by a distance greater than the spacing of said sets of alterations, said shoes extending laterally beyond said physical alterations and a roller cooperating with said shoes for moving each of said sets of alterations beyond the bite of said feed roller and feed disks for resuming advancement of said strips.

17. In a manifolding machine, a platen adapted to support a plurality of superposed continuous strips each divided into a series of form lengths by transverse severing lines and each form length having two sets of feed-arresting, form-registering alterations, the first set comprising a pair of marginal notches transversely aligned across said strips, the second set comprising a pair of apertures aligned longitudinally with said notches to the rear thereof; means for advancing said plurality of strips comprising a pair of feed disks carried by a rotary shaft, said disks being in alignment with said marginal feed-arresting, form-registering alterations and a roller cooperating with said disks, said feed disks cooperating successively with said notches and apertures to interrupt the advancement of said strip twice during the feeding of each form length for accurately registering the superposed strips transversely and longitudinally by the time a severing line between two successive form lengths attains a predetermined severance point on the machine; and restarting means comprising

ing a pair of starter shoes carried by each of said disks arcuately spaced apart by a distance greater than the spacing of said notches and apertures and extending inward from said feed disks beyond the limits of said alterations, and a roller cooperating with said shoes, for moving said notches and apertures beyond the bite of said feed disks and feed roller for resuming advancement of said strips.

18. In a manifolding machine, a platen adapted to support a plurality of superposed continuous strips each divided into a series of form lengths by transverse severing lines and each form length having two sets of feed-arresting, form-registering alterations, the first set comprising a pair of marginal notches, the leading edge of which coincides with said transverse severing lines, and the other set comprising a pair of apertures within each form length longitudinally aligned with said notches and positioned to the rear thereof; a severing station upon said machine; means disposed ahead of said severing station for advancing said plurality of strips toward said severing station comprising a pair of feed disks in alignment with said notches and apertures carried by a rotary shaft, and a roller cooperating with said disks, said feed disks cooperating successively with said sets of alterations to interrupt the advancement of said strips twice during the feeding of each form length, cooperation of said disks with said notches registering said superposed strips longitudinally, and cooperation of said disks with said apertures accurately registering said superposed strips transversely and longitudinally by the time a severing line between two successive form lengths attains said severance station on the machine; restarting means comprising a pair of starter shoes carried by said disks arcuately spaced apart by a distance greater than the spacing between said notches and apertures in each form length and extending inwardly from said disks beyond said notches and apertures, and a roller cooperating with said shoes for moving each of said sets of alterations beyond the bite of said feed disks and feed roller for resuming advancement of said strips; and releasable stop means for arresting operation of said feed disks when said severing line attains said severance

station, said feed disks reengaging the superposed strips by the time said severing line attains said severing station.

19. A strip-feeding disk adapted to cooperate with a series of feed-arresting, form-registering apertures in a plurality of superposed strips of manifolding stationery for arresting advancement of said strips and registering the superposed form lengths thereof, said disk having a plurality of arcuately spaced starting shoes laterally offset from the strip-engaging surface of the disk for resuming advancement of said manifolding stationery.

20. In a manifolding machine, a platen adapted to support a plurality of superposed continuous strips each divided into a series of form lengths by transverse severing lines and each form length having two sets of feed-arresting, form-registering alterations, said sets of alterations being spaced apart and mutually aligned longitudinally of said strips; means for advancing said plurality of strips comprising a pair of feed disks carried by a rotary shaft, said disks being in alignment with said feed-arresting, form-registering alterations and a roller cooperating with said disks, said feed disks cooperating successively with said sets of alterations to interrupt the advancement of said strips twice during the feeding of each form length for accurately registering said superposed strips transversely and longitudinally by the time a severing line between two form lengths attains a predetermined severance point on the machine; and restarting means comprising a pair of starter shoes carried by said feed disks and extending laterally beyond said physical alterations and a roller cooperating with said shoes, for moving said sets of alterations beyond the bite of said feed roller and feed disks to resume advancement of the strips, said shoes being arcuately spaced apart on the periphery of said disks by a distance greater than the spacing of said sets of alterations in each form length, and the remainder of the periphery of said disks exceeding the distance between adjacent sets of alterations in successive form lengths, whereby one rotation of said feed disks is adapted to feed one form length of said strips.

WILLIAM G. BORCHERS.
